Primary Examiner—Ruth McInroy*Attorney, Agent, or Firm*—Leydig, Voit & Mayer, Ltd.[57] **CLAIM**

The ornamental design for the combined two burner cook top with open burners, as shown as described.

DESCRIPTION

FIG. 1 is a top perspective view of a combined two burner cook top with open burners showing our new design, the counter top into which the cook top is normally recessed is shown in broken lines for illustrative purposes only and forms no part of the claimed design;

FIG. 2 is a top view thereof;

FIG. 3 is a front view thereof;

FIG. 4 is a back view thereof;

FIG. 5 is a side view thereof; and,

FIG. 6 is a side view thereof showing the side opposite that shown in FIG. 5.

The bottom frame of the cook top shown in broken lines in FIGS. 1 and 3-6 is for illustrative purposes only and forms no part of the claimed design.
